UNITED STATES PATENT OFFICE.

NATHANIEL S. REEDER, OF CHICAGO, ILLINOIS, ASSIGNOR TO PRESSED STEEL CAR COMPANY, OF PITTSBURGH, PENNSYLVANIA, A CORPORATION OF NEW JERSEY.

DOOR-OPERATING MECHANISM.

1,202,313.

Specification of Letters Patent. Patented Oct. 24, 1916.

Application filed August 25, 1914. Serial No. 858,563.

To all whom it may concern:

Be it known that I, NATHANIEL S. REEDER, a citizen of the United States, residing at No. 5318 East End Boulevard, Chicago, in the county of Cook and State of Illinois, have invented certain new and useful Improvements in Door-Operating Mechanism, of which the following is a specification.

An object of the present invention is to provide a door operating mechanism for railway cars by means of which the discharge doors of a car may be moved to and held stationary in any desired position to permit the gradual and regulated discharge of the lading, as in ballasting; or if desired may be allowed to move to full open position without regulation, when a quick discharge of the lading is desired.

Another object of the invention is to provide a mechanism for regulating the speed of opening discharge doors which are operated by a non-regulated mechanism.

Another object of the invention is to provide means for connecting and disconnecting the mechanism for producing a regulated opening of the door and the mechanism for producing a non-regulated opening of the door.

A further object of the invention is to provide means for locking the regulating operating mechanism in and out of engagement with the non-regulating operating mechanism.

Referring now to the drawings, in which like reference characters refer to like parts, Figure 1 is a plan view of a portion of a car having one form of the door operating mechanism applied thereto; Fig. 2 is a side elevational view of the same; Fig. 3 is an enlarged plan view of a portion of the car with the floor plates removed to more clearly show the invention; Fig. 4 is a sectional view taken on the line 4—4 of Fig. 3 showing the regulating mechanism in engagement with the non-regulating mechanism; Fig. 5 is a like view showing the mechanisms out of engagement; Fig. 6 is a sectional view taken on the line 6—6 of Fig. 3. Fig. 7 is an enlarged plan view of a portion of a car with a modified form of the invention applied thereto, the floor plates being removed to more clearly show the invention; Fig. 8 is a sectional view of the same taken on the line 8—8 showing the regulating mechanism in engagement with the non-regulating mecha-

nism; Fig. 9 is a like view showing the regulating mechanism out of engagement with the non-regulating mechanism; Fig. 10 is a sectional view taken on the line 10—10 of Fig. 8, and Fig. 11 is a sectional view taken on the line 11—11 of Fig. 7. Fig. 12 is an enlarged plan view of a portion of a car with a further modified form of the invention applied thereto, portions of the floor plate being removed to more clearly show the invention; Fig. 13 is a sectional view of the same taken on the line 13—13; and Fig. 14 is a sectional view taken on the line 14—14 of Fig. 12.

There are various types of cars to which the hereinafter described mechanisms may be applied, but as an illustration, a hopper car has been shown in the drawings, which comprises center sills 1, 1, side walls 2, end sloping floor sheets 4, longitudinal ridges 5, central sloping floor sheets 6, outside hopper sheets 7 and inside hopper sheets 8, all of which are secured together in a suitable manner.

9, 9 indicate two of the discharge doors which are located one on either side of the center sills 1, 1 and which at their upper edge portions are hinged to members 10 secured near the lower edge portions of the sloping floor sheet 4. At their lower edge portions these doors are connected together by members 11, 11.

In the drawings a suitable quick or non-regulating door operating mechanism has been illustrated, having a crank 12 operatively connected with an operating shaft 13, which is suitably mounted near its outer end, in a member 14 secured to the outside hopper sheet. The outer end portion of this shaft is made square so that a wrench may be applied thereto to rotate it, and is also provided with a ratchet wheel 15 with which a pawl 16 is adapted to engage. The crank 12 comprises spaced arms 17, 17 which are connected together by a web 18, and also comprises trunnions 19 and 20, which trunnions are journaled in the bracket members 21 secured to the center sills 1, 1.

22 indicates an actuating rod or link which is pivotally secured at one end to the members 11, 11 which are secured to the discharge doors 9, 9, and which is pivotally connected at its other end to the arms 17, 17 of the crank 12. When the doors 9, 9 are in closed position the link or rod 22 rests on the

- web 13 of the crank 12. It will be seen that the centerline of the link has passed the dead center of the crank arms 17, 17, thus locking the doors in closed position.
- 5 23 indicates an operating shaft which at its outer end is suitably journaled in a member 24, and which at its inner end is slidably mounted and held against longitudinal movement in a member 25 secured 10 to the center sill 1. Between the members 24 and 25 the shaft 23 is provided with a worm 26 which may be keyed or otherwise secured thereto and which is adapted to be moved into and out of operative engagement 15 with the teeth 27 of the worm wheel or quadrant 28 secured to the trunnion 20 of the crank 12. The worm 26 is provided with an extension 30 which is preferably integral therewith and which is journaled 20 in a link bearing member 31. This bearing member is pivotally connected with an arm 32 of a lever 33. The lever 33 besides having an arm 32, has also arms 34 and 35; the arm 34 being pivotally connected to the 25 member 25, and the arm 35 being pivotally connected with one end of a rod or link 36. At its other end this rod or link 36 is provided with a lug 37 and is bent as at 38, and is pivotally connected with a crank 30 arm 39 secured to an operating shaft 40. On the outer end portion of this shaft 40 a lever or wrench 41 is provided by which the shaft may be rotated. It will be noted that the rod or link 36 passes over the operating shaft 39 and that the connection 35 between the crank arm 38 and the rod or link 36 is beyond the center of such shaft, thus locking the worm 26 in engagement with the worm wheel or quadrant 28.
- 40 When it is desired to open the discharge doors of a car by the use of the preferred form of the regulating mechanism, as shown in Figs. 1, 2, 3, 4 and 6 of the drawings, the pawl 16 is first thrown out of engagement with the ratchet wheel 15. The hand wheel 41, secured to the operating shaft 23, is then rotated in the direction indicated by the arrow in Fig. 1 which causes the worm 26 to move the worm wheel or 45 quadrant 28, crank 12 and actuating rod 22 in the direction indicated by the arrow in Fig. 4. It will be seen from the foregoing description that the operator has control of the operating mechanism at all times and that the discharge doors may be opened to any desired position and be held in such position. In the drawings a lug 42 has been shown which is preferably integral with the worm wheel or quadrant 28. This 50 lug is adapted to engage the end of the worm 26 and limit the movement of the door operating mechanism to produce a maximum door opening of predetermined extent, and also to prevent the quadrant 28 55 from being turned so far in the direction

of the arrow shown in Fig. 4, that it may lose its engagement with the worm 26.

When it is desired to open the discharge doors with the use of the regulating mechanism, the shaft 40 and the crank arm 39 70 are rotated in the direction, as indicated by the arrow in Figs. 4 and 5, by moving the lever or wrench 41 to the position, as shown in dotted lines in the drawings, thus moving the rod or link 36 away from the shaft 75 until such time as the lug 37 engages the shaft, at which time the lever 33 has been moved a sufficient distance to disengage the worm 26 from the worm wheel or quadrant 28. When the lug 37 engages the shaft 40 80 the connection between the crank arm 39 and the link 36 has been moved to a position below the center of the shaft, thus locking the worm in a position out of engagement with the worm wheel or quadrant 85 28, the above operation is reversed.

In Figs. 7 to 11 inclusive a modification of the invention has been illustrated which 90 differs from the preferred form of the invention only in the mechanism for moving the worm 26 out of engagement with the worm wheel or quadrant 28 and the method of mounting the shaft 23 on the center sill 95 1. In this modified form a shaft 42' has been provided which is journaled in members 43, 43 secured to the center sills 1, 1. To this shaft a lever 44 is secured, which lever is pivotally connected with the rod or 100 link 36. A member 45 is secured eccentrically to the shaft 42' and is adapted to slidably engage and move an eccentric strap 46. This strap comprises parts 47 and 48 which are secured together, around the member 45, 105 by bolts 49. The part 48 of this strap, at its lower portion, is provided with spaced portions 50, 50 between which a block 51 is pivotally mounted, which block is adapted to receive the end portion of the shaft 23 110 and form a bearing therefor. The worm 26, in this form of the invention, is provided with an extension 52 which is adapted to be mounted in a slot in the bracket member 53 secured to the center sill 1, and engage such bearing member to prevent longitudinal movement of the shaft when the doors are being operated. It will be seen from Fig. 8 of the drawings, that when the shaft 42' is rotated in the direction as indicated by the arrow, that the member 45 will move the strap 46 and shaft 23 to the position as shown in Fig. 9. When the shaft 23 is being moved to this position the block 51 slides on the shaft and also adjusts itself 115 to the inclination or angle of the shaft. To rotate the shaft 42' substantially the same means have been employed as those hereinbefore described in connection with the preferred form of the invention.

In Figs. 12 to 14 inclusive a further modification of the invention has been illustrated in which the non-regulating door operating mechanism is the same as that hereinbefore described in connection with the preferred form of the invention. In this modified form of the invention, the lower end portion of the shaft 23 is suitably mounted in an arm 54 which is pivotally mounted on a member 55 secured to the center sill 1. The end portion 56 of this arm is movably mounted in a bracket member 57 secured to the center sill 1, and to hold the worm 26 in engagement with the worm wheel or quadrant 28, a bolt 58 or other equivalent means is passed through perforations in the flange 59 of the arm 54, and a perforation in the flange 60 of the bracket member 57, and is held in position by a nut 61. When it is desired to disengage the worm 26 from the worm wheel or quadrant 28, the bolt 58 is removed and the arm 54 moved to the position, as shown in dotted lines in Fig. 13 at which time the bolt 58 is again passed through the perforation in the flange 59 of the arm 54 and through a perforation in the flange 60 of the bracket member 57, and is held in this position by the nut 61, thus locking the worm in a position out of engagement with the worm wheel or quadrant 28.

In the drawings of this application, my invention has been illustrated in its adaptation to what is known as a hopper car, but it is to be understood that this invention may be applied to other types of cars, and to many types of door operating mechanisms, which do not regulate the amount of opening of the doors; and, while details of the invention have been illustrated in the drawings, I do not wish to be limited to such details, since

What I claim is:

1. The combination with a non-regulating discharge door operating mechanism, of a regulating mechanism adapted to be moved into or out of positive operative engagement with said operating mechanism, and link means for moving said regulating mechanism.

2. The combination with a car of a discharge door therefor, a mechanism for operating said door without regulation, a mechanism adapted to be moved into engagement with said first mentioned mechanism to operate said door with regulation, and means for moving said last mentioned mechanism, said means comprising a lever, a member connecting said last mentioned mechanism and said lever, an operating shaft for said lever, and a link operatively connecting said lever and operating shaft.

3. The combination with a non-regulating discharge door operating mechanism of a regulating mechanism adapted to operatively and positively engage therewith, and

means for moving said regulating mechanism into and out of engagement with said non-regulating mechanism, said means comprising a plurality of links and a lever interposed between and operatively connecting 70 said links.

4. The combination with a non-regulating discharge door operating mechanism, of a regulating mechanism adapted to operatively engage therewith, and means for moving and automatically locking said regulating mechanism in and out of engagement with said non-regulating mechanism, said means comprising a pivotally mounted member, and link means for operating said 80 member.

5. The combination with a non-regulating discharge door operating mechanism, of a regulating mechanism adapted to be moved and locked in and out of positive engagement with said non-regulating mechanism, and link means for moving and automatically locking said regulating mechanism in and out of engagement with said non-regulating mechanism.

6. The combination with a non-regulating discharge door operating mechanism, of a regulating mechanism adapted to be moved into or out of operative engagement with said operating mechanism, said regulating 95 mechanism comprising an operating shaft and a worm, a lever for moving said regulating mechanism, and means for operating said lever.

7. The combination with a non-regulating discharge door operating mechanism, of a toothed member secured thereto, a regulating mechanism adapted to be moved into or out of engagement with said member, said mechanism comprising an operating shaft and link means connected with said shaft for moving said regulating mechanism.

8. The combination with a non-regulating discharge door operating mechanism of a toothed member connected therewith, a regulating mechanism adapted to be moved into or out of operative engagement with said member, and a stop on said toothed member adapted to engage said regulating mechanism.

9. The combination with a non-regulating discharge door operating mechanism of a regulating mechanism independent of said operating mechanism adapted to be moved into or out of positive engagement with said operating mechanism, and a stop on said non-regulating mechanism adapted to engage said regulating mechanism when said regulating mechanism is in engagement with said non-regulating mechanism.

10. In a car, the combination with a discharge door therefor, of a mechanism for operating said door, an independent mechanism adapted to positively engage and regulate the movement of the first said mecha-

nism, and means on the first said mechanism adapted to engage said independent mechanism and limit the movement of the first said mechanism.

- 5 11. In a car, the combination with a discharge door therefor, of a mechanism for operating said door, movable means adapted to positively engage said mechanism and regulate the movement thereof, and means on one 10 of said mechanisms adapted to engage the other of said mechanisms to limit the movement of such mechanisms when the doors are being opened.

12. In a car, the combination with a discharge door therefor, of a mechanism for operating said doors, actuating means adapted to be moved into positive engagement with said mechanism to regulate the movement thereof, and a stop on one of said mechanisms adapted to engage the other of said mechanisms.

13. The combination with a car, of a discharge door therefor, a crank connected with said door, a trunnion for said crank, a toothed member on said trunnion, and a plurality of shafts for operating said crank, one of said shafts being permanently connected with said crank and the other of said shafts being movable into or out of engagement 30 with said toothed member.

14. The combination with a car, of a discharge door therefor, a crank connected with said door, a shaft connected with said crank for effecting a non-regulated movement thereof, a trunnion on said crank, a toothed member on said trunnion and a second shaft adapted to be moved into operative engagement with said toothed member for effecting a regulated movement of said crank.

- 40 15. The combination with a car, of a discharge door therefor, a crank connected with said door, a trunnion on said crank, a toothed member on said trunnion, a plurality of shafts for operating said crank, a worm on one of said shafts adapted to be moved into operative engagement with said toothed member.

16. The combination with a car, of a discharge door therefor, a crank connected with 50 said door, a trunnion on said crank, a toothed member on said trunnion, a plurality of shafts for operating said crank, one of said shafts being movable into or out of engagement with said toothed member, and lever means for moving said shaft.

- 60 17. The combination with a car, of a discharge door therefor, a crank, a connection therefrom to the door, a trunnion on said crank, a toothed member on said trunnion, an operating shaft, a worm on said shaft adapted to operatively engage said member, and a lug on said member adapted to engage said worm to limit the movement of said crank when the door is being opened.

- 65 18. The combination with a car of a dis-

charge door therefor, a plurality of shafts for operating said door, means whereby the rotation of one of said shafts will effect a non-regulated movement of said door and worm gear means whereby the rotation of the other of said shafts will effect a regulated movement of the doors, and a stop for limiting the movement of said means when the doors are being opened.

19. The combination with a car, of a discharge door therefor, center sills, bracket members secured to said sills, a crank between said sills having trunnions mounted in said bracket members, connections from said crank to said door, a toothed member mounted on one of said trunnions, a plurality of shafts for operating said crank, one of said shafts being secured to said crank and the other of said shafts being movable into or out of engagement with said toothed member.

20. The combination with a car, of a discharge door therefor, center sills, bracket members secured to said center sills, a crank connected with said door, trunnions on said 90 crank journaled in said bracket members, an operating shaft secured to said crank, a toothed member on one of said trunnions, an operating shaft movably mounted above said toothed member, a worm on said shaft, and means for moving said worm into or out of engagement with said toothed member.

21. The combination with a car, of a discharge door therefor, center sills, bracket members secured to said center sills, a crank 100 connected with said door, trunnions on said crank journaled in said bracket members, an operating shaft secured to said crank, a toothed member on one of said trunnions, an operating shaft movably mounted above said toothed member, a worm on said shaft, and means operable from the side of the car for moving said worm into and out of engagement with said toothed member.

22. The combination with a car, of a discharge door therefor, center sills, bracket members secured to said center sills, a crank connected with said door, trunnions on said crank journaled in said bracket members, an operating shaft secured to said crank, a toothed member on one of said trunnions, an operating shaft movably mounted above said toothed member, a worm on said shaft, and link and lever means for moving said worm into or out of engagement with said 110 toothed member.

23. The combination with a non-regulating discharge door operating mechanism, of a regulating mechanism adapted to be moved into or out of engagement with said operating mechanism, and connected link and lever means for moving said regulating mechanism.

24. The combination with a non-regulating discharge door operating mechanism, of

- a regulating mechanism adapted to be moved into or out of operative engagement with said operating mechanism, a lever for moving said non-regulating mechanism, and 5 means for operating said lever, said means comprising an automatic lock for holding said regulating mechanism in or out of engagement with said non-regulating mechanism.
- 10 25. The combination with a non-regulating discharge door operating mechanism, of a regulating mechanism adapted to be moved into or out of operative engagement with said operating mechanism, a lever for moving said non-regulating mechanism, and means for operating said lever, said means comprising an operating shaft, a crank on 15 said shaft, and a link operatively connecting said crank and lever.
- 20 26. The combination with a non-regulating discharge door operating mechanism, of a regulating mechanism adapted to be moved into or out of operative engagement with
- said operating mechanism, a lever for moving said regulating mechanism, an operating 25 shaft, a crank on said shaft and a rod operatively connecting said crank and lever.
27. The combination with a non-regulating discharge door operating mechanism, of a regulating mechanism adapted to be moved 30 into or out of operative engagement with said non-regulating discharge door operating mechanism, means for moving said regulating mechanism, including an operating shaft and a rod operatively connecting said 35 means and said shaft, said rod being adapted to engage said shaft to lock said regulating mechanism into or out of engagement with said non-regulating discharge door operating mechanism. 40

In testimony whereof I affix my signature in presence of two witnesses.

NATHANIEL S. REEDER.
